(57) **CLAIM**

We claim the ornamental design for the rear gripper latch, as shown and described.

DESCRIPTION

FIG. 1 is a front perspective view of a rear gripper latch in its open, latched position in accordance with the present design;

FIG. 2 is a front perspective view of a rear gripper latch in its closed, unlatched position in accordance with the present design;

FIG. 3 is a front view of the rear gripper latch depicted in FIG. 1;

FIG. 4 is a rear view of the rear gripper latch depicted in FIG. 1;

FIG. 5 is a left side view of the rear gripper latch depicted in FIG. 1;

FIG. 6 is a right side view of the rear gripper latch depicted in FIG. 1;

FIG. 7 is a top view of the rear gripper latch depicted in FIG. 1;

FIG. 8 is a bottom view of the rear gripper latch depicted in FIG. 1;

FIG. 9 is a front view of the rear gripper latch depicted in FIG. 2;

FIG. 10 is a rear view of the rear gripper latch depicted in FIG. 2;

FIG. 11 is a right side view of the rear gripper latch depicted in FIG. 2;

FIG. 12 is a left side view of the rear gripper latch depicted in FIG. 2;

FIG. 13 is a top view of the rear gripper latch depicted in FIG. 2;

FIG. 14 is a bottom view of the rear gripper latch depicted in FIG. 2; and,

FIG. 15 is a left side perspective view of the rear gripper latch depicted in FIG. 1.

The broken lines are directed to the environment surrounding the rear gripper latch and form no part of the claimed design.
